F. ROBINSON.

SPARK PLUG.

APPLICATION FILED JULY 15, 1918.

1,347,662.

Patented July 27, 1920.

FIG. 1

UNITED STATES PATENT OFFICE.

FRANK ROBINSON, OF CHICAGO, ILLINOIS.

SPARK-PLUG.

1,347,662.

Specification of Letters Patent. Patented July 27, 1920.

Application filed July 15, 1918. Serial No. 245,045.

To all whom it may concern:

Be it known that I, FRANK ROBINSON, a citizen of the United States, and a resident of the city of Chicago, in the county of Cook and State of Illinois, have invented certain new and useful Improvements in Spark-Plugs; and I do hereby declare that the following is a full, clear, and exact description of the same, reference being had to the accompanying drawings, and to the numerals of reference marked thereon, which form a part of this specification.

In the construction of spark plugs considerable trouble is usually experienced in properly adjusting the spark plug terminals a proper distance apart to produce sparking. The difficulty has been found to exist in the construction of the terminal parts, which when assembled often fail to afford a proper spark gap, resulting in the faulty operation of the spark plug.

This invention relates to an improved form of an internal combustion engine spark plug wherein the spark plug terminal members are so constructed that when assembled within the spark plug they are properly positioned with respect to one another to produce a desired spark gap, without necessitating any adjustment of parts.

It is an object of this invention to construct a spark plug provided with terminal members which when assembled, due to their construction, are always properly spaced from one another to provide a desired spark gap.

Another object of the invention is the construction of a spark plug having the terminal members spaced in overlapping position with respect to each other to insure a proper spark gap therebetween.

It is a further object of the invention to provide a spark plug having the spark plug terminal members axially aligned with one another to afford a proper spacing of the terminal pins between adjacent sides thereof.

It is furthermore an object of the invention to provide a spark plug having the spark terminals spaced side by side.

It is an important object of this invention to construct a spark plug wherein spaced overlapping terminals form part of axially aligned spark plug terminal members for insuring the proper spacing of the terminals when the plug is assembled.

Other and further important objects of

this invention will be apparent from the disclosures in the specification and drawings.

The invention (in a preferred form) is illustrated in the drawings and hereinafter more fully described.

On the drawings:

Figure 1 is a side elevation of a spark plug embodying the principles of this invention.

Fig. 2 is a section taken on line 2—2, of Fig. 1, with parts shown in elevation.

Fig. 3 is a sectional view taken on line 3—3, of Fig. 2.

Fig. 4 is a section taken on line 4—4, of Fig. 2.

Fig. 5 is a section taken on line 5—5, of Fig. 2.

Fig. 6 is an enlarged fragmentary detail section taken through the lower end of the spark plug and showing the method of mounting the lower terminal member in position.

Fig. 7 is a central vertical section of the lower terminal member, with parts in elevation.

As shown on the drawings:

The reference numeral 1, indicates a metal spark plug sleeve, base member or shell, having an externally threaded open plug 2, integrally formed on the lower end thereof, and an internally threaded integral hexagonal nut portion 3, formed on the upper end thereof to permit a wrench to be engaged therewith for mounting the base on an engine cylinder. Formed within the base 1, is an upper annular shoulder 4, and a lower annular shoulder 5. The lower end of the plug 2, is beveled or tapered as denoted by the reference numeral 6, and is axially drilled to afford a recess 7, and a sharp annular edge or rim 8.

A lower electrode or terminal member is rigidly secured axially in the plug 2, and comprises a metal stem, spindle or post 9, the upper end of which is reduced in diameter to afford a shoulder upon which is securely seated a downwardly curved hood or baffle plate 10. Rigidly secured axially in the upper end of the post 9, and projecting thereabove is a spark terminal pin or electrode tip 11. Riveted or otherwise rigidly secured axially to the lower end of the post 9, is a flat steel ring, spider or stamping 13, provided with gas ports or openings 110

- 14, between the radial spokes 15, thereof. The lower electrode 9—15, is projected axially into the lower open end of the base plug 2, to permit the gas ported spider 13, 5 to seat in the plug recess 7. To rigidly hold the lower electrode co-axially disposed in position within the plug 2, the metal rim 8, is forced inwardly beneath the spider 13, to form a retaining bead 16.
- 10 Removably disposed within the base 1, is an axially passaged insulating member or core made of porcelain or other suitable insulating material. Said core comprises a neck 17, an enlarged collar or intermediate 15 portion 18, and a chambered tail portion 19, all integral. Disposed upon the shoulder 4, is a packing ring or washer 20, and seated thereon is the lower end of the core collar 18. The chambered tail portion 19, of the 20 porcelain core projects into the plug portion 2, of the base to within a short distance of the shoulder 5, and communicates with a chamber in the lower portion of the plug 2, to form a combustion chamber 21.
- 25 Projecting axially through the longitudinally passaged insulating core is a priming tube 22, externally threaded at both projecting ends thereof. Disposed around the lower projecting end of the priming tube 30 is a washer 23, which is held in position against the porcelain core by means of a lower electrode or terminal member embracing an internally threaded ring or nut 24, having integrally formed at one side of 35 the lower end thereof a terminal pin or electrode tip 25, which projects downwardly parallel and to one side of the lower terminal pin 11, and properly spaced therefrom to afford a spark gap. Due to the co-axial 40 arrangement of the lower electrode member and the upper electrode member, the terminal tips 11 and 25, when the spark plug is assembled, are always properly spaced side by side with the proper spark gap therebetween. The electrode ring 24, and the 45 washer 23, are locked in sealing relation with the core, by means of a packing 26, and a knurled lock ring 27, which is threaded upon the upper projecting end of the 50 priming tube 22. The lock ring 27, seats tightly against the upper end of the porcelain core neck 17, holding said packing 26, seated around the tube in a recess formed for the purpose in the upper end of the 55 core neck 17.
- Removably threaded upon the upper projecting end of the priming tube 22, above the lock ring 27, is a priming mechanism 28, which communicates with the passage in 60 said priming tube.
- To removably hold the porcelain core in position seated within the base 1, a threaded gland or lock nut 29, is threaded into the upper internally threaded nut portion 65 3, of said base, and presses against a washer 80, resting on the enlarged portion 18, of the core to clamp the core in place sealed and axially aligned within the base.
- The co-axial arrangement of the parts of the spark plug, permits the same to be 70 quickly assembled and insures a proper spacing of the electrode tips 11 and 25, without requiring any adjustment. It will also be noted that all of the spark plug parts may be readily removed for cleaning or 75 repairs.
- I am aware that numerous details of construction may be varied through a wide range without departing from the principles of this invention, and I therefore do not 80 purpose limiting the patent granted otherwise than necessitated by the prior art.
- I claim as my invention:
1. A spark plug embracing a base, an electrode axially disposed therein, an insulating 85 member axially seated within said base and having a chamber therein into which said electrode projects, priming means axially secured within said insulating member, and a second electrode secured on said priming 90 means within said chamber and overlapping said first electrode to form a spark gap between the adjacent sides of said electrodes.
  2. A spark plug comprising a base, an electrode axially disposed therein, an insulating 95 member seated axially in said base and inclosing the upper end of said electrode, means for holding said insulating member secured in position, priming means projecting axially through said insulating 100 member, a ring secured on the lower projecting end of said priming means within said insulating member, and an electrode formed on said ring to one side thereof and spaced to one side of said first mentioned 105 electrode within said insulating core.
  3. A spark plug comprising a shell, a chambered plug formed on the lower end thereof, a chambered insulating core within said shell registering with said chambered 110 plug to form a combustion chamber, and spark terminals secured to said plug and to said core, said spark terminals overlapping one another within said insulating core and spaced apart to form a spark gap between 115 the adjacent sides thereof.
  4. In a spark plug, a base having a recess in the lower end thereof, an apertured stamping rigidly seated therein, a rod secured thereon and projecting axially into 120 said base, baffle cleaning means mounted on said rod, an electrode mounted in the upper end of said rod and co-axial therewith, an insulating core seated within said base, means for removably holding said core axially within said base, a priming tube projecting axially through said core, a ring secured on the lower end thereof above said 125 first mentioned electrode, a second electrode integrally formed on the bottom and to one 130

side of said ring, said second electrode disposed parallel and to one side of said first mentioned electrode and properly spaced therefrom to form a spark gap, and priming means secured on the upper end of said priming tube for holding said tube and ring in position.

5. In a spark plug, a base having the lower end tapered and recessed to form a rim, an apertured stamping seated in said recess, said rim adapted to be engaged under said stamping to rigidly hold the same in position, a post rigidly secured centrally on said stamping and projecting axially into 10 said base, a baffle on said post, a lower electrode tip secured axially in the upper end of said post, an insulating core removably secured co-axially in said base, means projecting axially through said core, a member 15 removably secured on the lower projecting end of said means, and an upper electrode

tip integrally formed on the bottom and to one side thereof and properly spaced to one side of said lower electrode tip to insure a proper spark gap between said upper and 25 lower electrodes when the spark plug is assembled.

6. In a spark plug, a chambered base, a chambered insulating core securely seated therein to form a combustion chamber within the spark plug, and electrodes secured to said base and core overlapping one another in the chamber of said insulating core and spaced apart to afford a spark gap there-between.

30 In testimony whereof I have hereunto subscribed my name in the presence of two subscribing witnesses.

35 FRANK ROBINSON.
